UNITED STATES PATENT OFFICE.

PEARL W. OSBORN, OF LOVELAND, COLORADO, ASSIGNOR OF ONE-HALF TO BENTON L. BONNELL, OF LOVELAND, COLORADO.

WRENCH.

1,105,372.

Specification of Letters Patent.

Patented July 28, 1914.

Application filed March 21, 1914. Serial No. 826,376.

To all whom it may concern:

Be it known that I, PEARL W. OSBORN, a citizen of the United States, residing at Loveland, in the county of Larimer and 5 State of Colorado, have invented certain new and useful Improvements in Wrenches; and I do hereby declare the following to be a full, clear, and exact description of the invention, such as will enable others skilled in 10 the art to which it appertains to make and use the same.

This invention relates to improvements in wrenches, and while it is peculiarly applicable for use as a pipe wrench, still it may be 15 used in other relations.

One of the objections to wrenches, as heretofore constructed, and especially to that type, wherein a wheel or lever is employed to adjust the jaws, is that they cannot always 20 be used satisfactorily in restricted spaces, and the wheel or lever often strikes against an obstruction, causing the wheel or lever to move and release the jaws from the work. On the other hand, the jaws become so 25 firmly locked in some cases, that in restricted or close spaces it is difficult to operate the wheel or lever to release the jaws from the work. These conditions particularly prevail where the working parts of the wrench are 30 rusty or clogged, or in cold weather when the fingers of the operator are more or less numb.

The primary object of the present invention, therefore, is to provide a wrench that 35 is durable and simple in construction and operation, inexpensive to manufacture, efficient in action, and the parts of which can readily be dis-assembled and re-assembled, and any broken or worn parts replaced.

Another object of the invention is to provide a wrench that is substantially of uniform size from the head of the wrench to the handle, and which has no projecting levers or other parts, the adjustment elements being incased or substantially self contained, so that the wrench may be satisfactorily used in restricted or close places.

A further object is to provide a wrench, the jaws of which may be operated directly 50 into engagement with the work by a quick action and without lost motion, saving considerable time, and providing a wrench that can be worked in close places where others may not be worked.

A still further object of the invention is

that the spring controlling the pawls and the pivoted jaw holds the latter up against the work, so that should the handle be released the wrench will not fall from the work, avoiding accidents and injuries to workmen 60 below.

With these and other objects in view, the invention consists of the novel features of construction and in the combination and arrangement of parts, as will be more fully 65 described in the following specification and particularly pointed out in the appended claims.

It will be obvious, however, that minor changes might be made in the construction 70 and arrangement of parts without departing from the spirit of the invention, and without sacrificing any of the vital principles thereof, and while the invention is not limited, therefore, to the exact details as 75 shown and described, still for the purpose of a full disclosure reference is had to the accompanying drawings illustrating a practical embodiment of the invention, in which drawings like characters designate the same 80 parts in the several views, and in which—

Figure 1, is a view in elevation of the wrench in its operative position. Fig. 2, is an enlarged sectional view of the same, the handle being omitted. Fig. 3, is a cross sectional view on the line 3—3 of Fig. 2, and Fig. 4, is a cross sectional view on the line 4—4 of Fig. 2.

1 designates the shank of the wrench, which may have a tapering stem, shown in 90 dotted lines in Fig. 1, and provided with a threaded tip, on which is screwed a nut 2, the stem being incased by the usual grip or handle member 3. On one edge face the shank is serrated, forming a series of ratchet 95 teeth 4, and on the end of the shank there is carried a serrated jaw 5, shown in the drawings as comprising a fixed jaw relatively to the shank. On the shank 1, between the jaw 5 and the handle or grip 3, there is carried a support 6, which support and shank are slidingly mounted relatively to each other. This support 6 is in the form of a casing, having an open upper face 7, a hollow head 8, closed on its upper face by the 105 top wall 9, and separated from a lower hollow guide member 10 by the transverse wall 11, the bottom of the guide member being closed by a narrow bottom wall 12, and the forward edge being shaped as at 13 to con- 110

form to the rear edge face of the jaw 5, shown in the drawings as being beveled. The rear end of the casing is open on its lower face as at 14 and has a rear wall 15, slotted at 16, to allow of the passage of the shank therethrough.

As shown more clearly in Fig. 4, the inner faces of the side walls of the casing are vertically recessed as at 17 to receive and guide 10 one or a plurality of pawl members, the casing being so constructed as to not only form a sliding support for, but also to provide a housing for the said pawl members and for the pivoted end of the swinging jaw and 15 spring members, interposed between said swinging jaw and pawl members, all as hereinafter referred to.

While in carrying out the invention generally, one pawl alone might be employed, 20 still for the purpose of providing means for more closely adjusting the jaws, it is preferable to use a plurality of pawls, two of which are shown on the drawings, and they are of such a width that they overlap the 25 ratchet teeth, so that the pawls alternately or successively engage one of the toothed notches, thereby providing a closer adjustment of the jaws, somewhat after the fashion of the old form of screw threaded shank 30 and rotary sleeve or wheel adjustment. These pawls are slidably mounted in the recessed portions 17, and preferably consist of rectangular frame members 18 and 19, straddling the shank 1, the upper portions each 35 having a beveled tooth 18^a and 19^a, and the lower portions 18^b and 19^b projecting below the shank 1, through the open space 14, whereby the pawls may be readily manipulated by the user, to disengage the pawls 40 successively or alternately or collectively from the ratchet teeth. The swinging jaw 20 is provided with a shank or arm 21, pivotally mounted at its inner end, within the hollow head 8, by a pivot pin 22, the lower 45 edge face of the arm 21 normally resting on the upper edge face of the jaw 5, which may be slightly recessed, as illustrated in Fig. 2, to form a seat if desired.

The heel or inner end 23 of the arm 21 is 50 slightly spaced from the top 9 of the hollow head 8, and it is preferably curved, as shown in Fig. 2, to form a bearing or seat for one end of a springy or resilient element, interposed between said pivoted jaw shank and 55 said pawl or pawls. The spring element may be in the form of a flat resilient strip of proper curvature, one end of which engages the upper edge surface of the arm 21 forward of the pivot 22, and the other end of which engages the top edge surface of the pawl member.

Where a plurality of pawls are used, as 60 illustrated in the drawings, and two are preferable, the spring element is reversely curved, in the form of an ogee or S-shaped

curve, the short end or ends of which are disposed between the inside of the top wall 9 of the hollow head and the heel 23 of the arm 21, engaging said arm forward of the pivot 22, while the long end of the spring element is in the form of laminated or spaced strips 25 and 26, the lower spring arm or strip 25, being slightly shorter than the upper one 26, to seat respectively on top of the pawl members 18 and 19, as clearly 75 shown in Fig. 2, and the top surfaces of these pawl members may be recessed to receive snugly the ends of the springs as shown at 27 in Fig. 3 with reference to the pawl member 18.

28 is an internal stop, which instead of being formed integral with the bottom wall 11 of the hollow head, may as shown in the drawings be in the nature of a stud pin extending across the hollow head, forming an 85 abutment for the heel 23, whereby inordinate strain on the pawls is avoided, the thrust being more or less directed between the forward portion of the housing and the 90 shank of the wrench.

In view of the foregoing specific description, it is not believed to be essential nor desirable to further describe the operation of the wrench, as the same is believed to be manifest, and it is further obvious that the particular arrangement of the parts enables the springs to perform the dual function of always holding the swinging movable jaw up against the work, and at the same time controlling the action of the pawls.

What I claim is:—

1. In a wrench, the combination of a shank provided with a jaw and a series of ratchet teeth; a hollow sliding support mounted on said shank and forming a casing; a pawl member straddling said shank and slidably contained within said casing adjacent said ratchet teeth; a swinging jaw pivotally mounted on said casing; and a spring element directly interposed between and engaging said swinging jaw and pawl, substantially as described.

2. In a wrench, the combination of a shank provided with a jaw and a series of ratchet teeth; a hollow sliding support mounted on said shank and forming a casing; a pawl comprising a rectangular shaped frame member, surrounding said shank and slidably housed within said casing, said pawl member having an internal tooth at one end engaging said ratchet and at its other end projecting beyond said casing; a pivoted jaw mounted on said casing; and a spring element interposed between and operatively engaging said pawl member and pivoted jaw, substantially as described.

3. In a wrench, the combination of a shank provided with a jaw and a series of ratchet teeth; a hollow sliding support mounted on said shank and forming a casing having a

hollow head; a pawl member straddling said shank and slidably housed within said casing, said pawl member having an internal tooth at one end engaging said ratchet teeth 5 and at its other end projecting beyond said casing; a second jaw having an arm pivotally mounted in said hollow head, and having its upper edge face slightly spaced from the top of said hollow head; and a spring 10 element having one end disposed between the top of said hollow head and said pivoted jaw arm, and engaging the top edge face of the latter exteriorly of its pivotal axis, the other end of said spring element 15 operatively engaging said pawl member, substantially as described.

4. In a wrench, the combination of a shank provided with a jaw and a series of ratchet teeth; a hollow sliding support mounted on 20 said shank and forming a rear casing, and a forward hollow head surmounting a hollow guide member encompassing said shank and having an upper and lower wall slidably engaging the upper and lower edge 25 faces of said shank; a pawl member straddling said shank and slidably housed within said rear casing, said pawl member having an internal tooth at one end engaging said ratchet teeth and at its other end projecting 30 beyond said casing; a swinging jaw having an arm pivotally mounted in said forward hollow head; and a spring element disposed between and operatively engaging said pivoted jaw arm and said pawl member, substantially as described. 35

5. In a wrench, the combination of a shank provided with a jaw and a series of ratchet teeth; a casing slidably encompassing said

shank; a pawl member carried by said sliding casing and having a tooth engaging said 40 ratchet teeth; a swinging jaw having an arm pivotally mounted forward of said sliding casing; and a substantially ogee-shaped spring element interposed between and operatively engaging said swinging jaw arm 45 and said pawl member, substantially as described.

6. In a wrench, the combination of a shank provided with a jaw and a series of ratchet teeth; a casing slidably encompassing said 50 shank; a plurality of pawl members straddling said shank and arranged face to face within said casing, each of said pawl members having a tooth at one end alternately engaging said ratchet teeth in locking position in one direction of movement, and at their other ends projecting slightly outside of said casing to provide means for releasing said pawl teeth successively or collectively in the reverse direction of movement; a swinging jaw having an arm pivotally mounted to said casing; and a spring element having one end operatively engaging said pivoted jaw arm, and at its other end having separated spring leaves each operatively 55 engaging one pawl member, and the said pawl members and spring element being substantially self contained within said casing to avoid unnecessary projecting parts, substantially as described. 60

In testimony whereof, I affix my signature, in presence of two witnesses.
